UNITED STATES PATENT OFFICE.

FRANZ WSEWOLOSCHSKY, OF BREMEN, GERMANY, ASSIGNOR OF ONE-HALF TO B. HOLTHAUS, MASCHINENFABRIK A. G. DINKLAGE, GERMANY.

SEED FEEDER.

Application filed December 28, 1925, Serial No. 77,994, and in Germany April 20, 1924.

Machines for sowing single grains with depositing wheel by which the seed-grains gripped by means of an oscillating gripper, are singly deposited in the ground, have been known. The grippers of known type in the shape of tongs present, however, the inconvenience that the grains are easily damaged.

According to this invention the grippers are constructed as forks having conical ends with elastic prongs which are conducted along stationary strippers, whereupon the grains are delivered through a tube to the depositing wheel. The grippers, which are oscillating in the well known manner, are further arranged the one behind the other in great number and separately from the depositing wheel on a disk mounted above the depositing wheel. The construction of the machine in general is further improved as will be hereinafter described and shown by way of example in the accompanying drawings, in which

Fig. 1 is a partial side elevation of the machine.

Fig. 2 shows in side elevation, on larger scale than that used in Fig. 1, the gripping apparatus.

Fig. 3 is a front elevation of Fig. 2.

Fig. 4 shows the gripper alone in front elevation and in side elevation, on a larger scale than used in Figs. 2 and 3.

In the top part of a reservoir *a* containing the seed-grains a gripper disk *b* is rotatably mounted on which disk *b* the grippers *d* are pivotally mounted by means of pivots *c*, said grippers being designed to feed the grains singly to a discharge tube *e* through which the grains are conducted into a depositing wheel *f*. As shown, this tube has a flaring upper inlet end formed with guide slots *e'* at two diametrically opposite sides thereof.

As shown in Fig. 4 each gripper *d* consists of a fork having two prongs the ends of which are slightly bent outward so that when a gripper is pushed into a heap of grains one grain will always be jammed between the prongs without being damaged. The prongs *d*, *d*₂ are elastic. A stripper *g* is supported upon one of the slotted walls of tube *e*, so as penetrate between the prongs of each grip-

per. The front edges of the prongs *d*, *d*₂ of each gripper are partly connected so that the gripper when passing along the stripper *g* is partly guided on said stripper.

With this object in view the elastic grippers are made, as shown in Fig. 4, from a piece of sheet metal bent to form a channeled or U-shaped body portion comprising a pair of side walls *h* united at one edge by a transverse bridge wall *h'*, the bridge wall being of less length than the side walls or cut away at the point *i* (Fig. 4), leaving the outer extremities of the walls *h* free and forming the resilient gripping prongs or jaws *d*'—*d*². By this construction the resilient jaws are made with the body portion of the gripper of a unitary piece of material, thus securing simplicity and economy of construction, and also by such construction the body portion of each gripper is formed with a longitudinal guide groove or channel disposed in alinement with the space between the jaws *d*'—*d*². The walls *h'*, stiffened by the wall *h*, furthermore sufficiently stiffen the jaws *d*'—*d*² to properly limit their amplitude of flexibility. By providing a unitary construction of gripper of the character described, inherently flexible gripping jaws are produced, obviating the necessity of hinging the jaws to the body portions of the gripper and of providing auxiliary springs for making the jaws resilient.

As the grippers are pivotally mounted on the rotating disk *b*, it will be evident that, in the rotation of said disk, the grippers will be carried around with the disk and at the same time will swing by gravity on their pivotal connections *c*. As each gripper reaches the lowest position in its orbit of rotation, it will accordingly drop by gravity so that its free end provided with the jaws *d*'—*d*² will depend into the hopper so that the jaws will come into engagement with and pick up a seed. On the further rotation of the disk, and as each gripper travels upward, it will gradually swing by gravity to a position in which it will lie within the line of the periphery of the disk, and as the pivoted end of each gripper comes above the inlet end of the dropper tube *e*, the gripper will drop by gravity into the guide slots *e'*.

and travel therein across the inlet end of the tube, thus being guided positively in its movements during the operation of discharging the seed from its jaws. As each gripper 5 comes into discharging position, its groove or channeled body portion first engages the stripper g and runs in guided connection therewith, the relative motion of the parts causing the stripper to pass from the guide 10 channel into the space between the gripping jaws, as the latter pass over the mouth or entrance end of the hopper, whereby at the limit of discharging motion of the gripper the stripper is brought into contact with the 15 seed held between the gripping jaws, whereby the seed is positively forced out of the jaws and into the discharge tube. This construction ensures an accurate bringing of the grippers into engagement with the stripper 20 per, and the latter into engagement with the gripped seed, so that a positive and measured working action will at all times be obtained.

As shown in Fig. 1 a wheel u having points designed to make holes in the ground 25 is coupled with the depositing wheel by a chain gear u_1 .

A guide wheel l is rotatably mounted on an oscillatable arm k . A depositing wheel f is rotatably mounted underneath the grain 30 reservoir a in a cylinder m . A guide funnel e is telescoped into a drop tube e_1 , which terminates in the depositing wheel f somewhat behind the centre of said wheel. The depositing wheel f is rotated by bevel wheel 35 transmission n, o from a vertical axle composed of two parts p, p_1 adjustable in vertical direction. The depositing wheel f has cavities r in its circumference. The wall s between the cavities r are of the same depth as 40 the cavities so that the mouth e_2 of the drop tube is closed for the same time as it is open. The drop tube e_1 terminates over the cavities r above the axle f_1 of the depositing wheel so that a cavity in which a grain has 45 been deposited must execute a rotation of more than 180° before the grain can drop out of the opening m_1 of cylinder m . On the cylinder m a guide wall m_2 is arranged for accurately guiding the grain which drops 50 out.

The angular speed of the depositing wheel f and the angular speed of the gripper disk b and further the distance of the cavities r with regard to one another are such that a 55 cavity r into which a grain has been dropped will have cleared the drop tube before another grain is dropped by a gripper so that only one grain can be dropped into one cavity.

Owing to the telescopic arrangement of the drop tube and of the driving axle for the depositing wheel f a uniform delivering of each grain into one cavity of said depositing wheel is ensured even if the fall head 65 is varied by unevenness of the ground. If

the fall head is reduced so that when the grain is dropped the mouth of the drop tube is not yet free the grain remains in the inclined mouth end of the drop tube until the cavity of the depositing wheel arrives under 70 the mouth of the drop tube. In order to prevent crushing of the grains the mouth e_2 of the drop tube has an enlargement e_3 in the direction of rotation of the depositing wheel f and further a radially directed edge 75 t . As the radial edge t extends in the direction of rotation of the depositing wheel f the grain rolls in the mouth e_2 of the drop tube without being crushed.

By the arrangement of the cavities in the depositing wheel, the adjustable drop tube and the adjustable driving axle, it is absolutely prevented that, even if the fall head should vary, more than one grain be deposited in each hole in the ground, and crushing of grains which should have been dropped prematurely is also prevented.

I claim:

1. In a seed feeder, a hopper, a discharge tube having an entrance end located above 30 the level of the seed in the hopper, a disk rotatable upon a horizontal axis, a stationary stripper arranged in proximity to the entrance end of the discharge tube, and grippers carried by the disk and pivotally 35 mounted to swing thereon in a direction transverse to the axis of the disk, said grippers having resilient gripping jaws at their free ends adapted to pick up the seed from the hopper, said grippers being movable in the rotation of the disk over the entrance end of the discharge tube and in such relation to the stationary stripper as to cause the latter to engage and release the seed from the gripper jaws at the moment of travel of 105 said jaws over the entrance end of the discharge tube.

2. In a seed feeder, a seed hopper, a discharge tube having an upper entrance end arranged above the level of the seed in the 110 hopper and provided with guide notches in diametrically opposite walls thereof a stationary stripper mounted on the hopper in alignment with said guide notches, a rotary disk mounted upon a horizontal axis, and grippers carried by said disk and pivotally mounted upon one side of said disk so as to swing within and without the line of its circumference, each of said grippers having a channeled body portion and spaced resilient 115 gripping jaws forming extensions of the walls of the channels, the construction being such that in the rotation of the disk the grippers will swing outwardly therefrom to cause their jaws to pick up seeds from the 120 hopper and so that at one point in their path of revolution, the grippers will engage and ride in the guide notches in the entrance end of the discharge tube and the channeled portions thereof will receive and engage the 125

stripper, whereby in the movements of the grippers the stripper will be guided into the spaces between the jaws to dislodge the seed therefrom.

- 5 3. A gripper according to claim 1, comprising a folded piece of sheet metal bent to provide a longitudinally channeled body

portion terminating at one end in inherently resilient gripping jaws forming extensions of the side walls of the channeled body por- 10 tion.

In testimony whereof I affix my signature.

FRANZ WSEWOLOSCHSKY.
